UNITED STATES PATENT OFFICE.

HENRY B. LEE, OF NEW LONDON, CONNECTICUT, ASSIGNOR TO THE D. E. WHITON MACHINE CO., OF NEW LONDON, CONNECTICUT, A CORPORATION.

DIRECT-READING PRESSURE-DIFFERENCE INDICATOR.

Application filed March 13, 1920, Serial No. 365,670. Renewed November 27, 1923.

To all whom it may concern:

Be it known that I, HENRY B. LEE, a citizen of the United States, residing at New London, in the county of New London and 5 State of Connecticut, have invented a new and useful Improvement in Direct-Reading Pressure-Difference Indicators; and I do hereby declare the following, when taken in connection with the accompanying drawings 10 and the characters of reference marked thereon, to be a full, clear, and exact description of the same, and which said drawings constitute part of this application, and represent, in—

15 Fig. 1, a view in side elevation of a steam-turbine provided with my improvement.

Fig. 2, a detached view in vertical longitudinal section showing my improved indicator as embodied in the follow-up pressure-regulator of the steam-turbine.

20 Fig. 3, a detached view in inside end elevation of the indicator.

Fig. 4, a detached view of the tapering oil-chamber of the indicator.

25 Fig. 5, a plan view thereof.

Fig. 6, a detached view of the pointer.

Fig. 7, a detached perspective view of the reciprocating prime-mover of the indicator.

30 Fig. 8, a view in vertical longitudinal section of one of the modified forms which my improvement may assume.

35 My invention relates to an improved direct-reading pressure-difference indicator for use in visualizing without calculation, the difference at any moment between the feed-water pressure and the steam pressure of a steam boiler system, the object being to provide a simple, convenient, and reliable apparatus for this purpose.

40 With these ends in view, my invention consists in a direct-reading pressure-difference indicator having certain details of construction as will be hereinafter described and pointed out in the claims.

45 For the illustration of my invention, I have shown it in Figures 1 to 7 inclusive, as applied to the follow-up pressure-regulator of a steam-turbine of the type used in turbo-pump installations, though my invention is 50 not so limited.

55 In carrying out my invention as herein shown, I mount a vase-shaped or flaring oil-chamber 2 by its sleeve 5^a in the reciprocating operating-head 3 of a follow-up pressure-regulator 4 of approved construction,

whereby the said chamber 2 is carried bodily by the head 3 and partakes of the reciprocating movement thereof. At its flaring upper end, the said oil-chamber 2 is bridged by a segmental index-plate 5 having graduations 6 indicating pounds of pressure and swept by a cross-piece at the upper end of an oscillatable indicator or pointer 7 which is actuated by means of a prime-mover in the form of a plunger 8 having free movement 60 in the relatively large axial passage 9 of the head 3.

The said plunger 8 is moved longitudinally in the said passage by the endwise pressure exerted upon its respective ends by 70 the diaphragms 10 and 11 of the follow-up pressure-regulator, the said head 3 being suspended by and between the said diaphragms of which the diaphragm 10 constitutes the inner wall of the water-pressure 75 chamber 12 and of which the diaphragm 11 forms the inner wall of the steam-pressure chamber 13. The chamber 12 is connected by a small pipe 14 with the boiler feed-water line of the system, while the chamber 13 is 80 connected by the small pipe 15 with the steam-service line thereof.

Interposed between the ends of the plunger 8 and the diaphragms 10 and 11, are thin metallic disks 16 which prevent the ends of 85 the plunger from being embedded, however slightly, in the softer material of the diaphragms 10 and 11, the ends of the head 3 being formed with annular clearance-chambers 17 concentric with its axial passage 9 so 90 as to permit the disks 16 to freely yield to inward pressures against them.

For the actuation of the pointer 7 by means of the plunger 8, the same is formed with a vertically arranged transverse slot 18 95 (Figure 7) through which the lower portion of the pointer passes downward to permit its knuckle-like fulcrum end 19 to enter a socket or bearing recess 20 leading out of the bottom of the axial passage 9 in the head 100 3, whereby the pointer is actually fulcrumed in the head 3 with which it bodily moves, as does also the flaring oil-chamber 2, as stated.

For the actuation of the pointer by the plunger 8, the pointer is formed just above 105 its knuckle 19 with a substantially circular bearing 21, the laterally opposite high points of which engage with the vertical side-walls of the slot 18, whereby endwise movement of the plunger 8 causes the pointer to be 110

swung correspondingly upon its fulcrum end 19. This movement of the plunger, though very slight, is greatly magnified at the upper end of the pointer.

5 A body of oil 22 located in the chamber 2 extends downward into the head 3 in which it is confined by the metal disks 16. The plunger 8 is thus virtually floated in oil, whereby it is made exceedingly sensitive, 10 while the pointer 7 is so far immersed in oil that it is prevented from undue vibration. The disturbing influences of the pump-impulses are thus eliminated from the pointer.

15 It will be apparent from the foregoing that differences in the pre-determined variation between the feed-water pressure and the steam pressure will be at once transformed by the movement of the diaphragms 20 10 and 11, into endwise movement of the plunger 8 which, acting as a prime-mover, will operate the pointer 7 which will, therefore, indicate the difference between the boiler feed-water pressure and the steam pressure 25 at any given moment. This difference will be indicated as a matter of direct-reading upon the scale 5 and without any mental calculation on the part of the observer; whereas, heretofore, the observer has been 30 obliged to consult two separate indicators and subtract the indication of one from the indication of the other in order to ascertain the excess pressure existing at the moment. The old method has the further 35 objection that it is open to errors in two instruments instead of one.

To provide for the operation of the plunger 8 by the diaphragms 10 and 11, their 40 central portions must be exposed to the full action of the pressures in the chambers 12 and 13. Thus, the retaining-washer 23 of the diaphragm 10 is formed with a relatively large central opening 23^a, while the retaining-washer 24 of the diaphragm 11 is formed 45 with a concentric sleeve 25 which provides for the exposure of the central portion of the diaphragm 11 as well as a means for supporting the inner end of the helical spring 26 provided for maintaining the 50 boiler feed-water pressure in excess of the steam pressure. The outer end of the spring 26 receives a flanged seat 27 counter-sunk for the reception of the inner end of an 55 adjusting-screw 28 by means of which the follow-up regulator is adjusted, as fully described in my co-pending application, filed May 14th, 1918, Serial Number 234,466.

While forming no part of my present invention, it may be explained that the follow-up pressure-regulator 4 is provided with a 60 regulator-lever 29 operated by the head 3 and co-acting with the extension 30 of a controller-lever 31 also acted upon by the spindle 32 of an emergency-governor, indicated by the numeral 33. The lower end of

the lever 31 is connected with the stem 34 of the valve of a steam-control valve located within the casing of a motor-controller, indicated by the reference numeral 35, as seen in Figure 1, which also shows 70 a turbine 36 having bearings 37 and one member 38 of a flange-coupling.

As shown in Figure 1 to 7 inclusive, my improvement is designed with particular reference to being incorporated in the follow-up pressure-regulator of a steam-turbine. Its use, however, is not so limited, as it is equally applicable for use by itself as an independent organization, and is so shown in Figure 8, in which the oil-chamber 2, index-plate 5, indicator 7, and plunger 8 are identical with the corresponding parts already described. In this construction, the vase-like oil-chamber 2 has its sleeve 5^a set into a spacing-member 39 instead of into a diaphragm head 3, as in the other construction, the said spacing-member being interposed between and supported by heads 40 and 41 bolted together by bolts 42. The head 40 contains a feed-water pressure chamber 43 connected by a pipe 44 with a boiler feed-water line, while the head 41 is formed with a steam-pressure chamber 45 connected by a pipe 46 with the steam service pipe of the boiler system. The respective ends of the plunger 8 impinge against diaphragms 47 and 48 interposed between the respective ends of the spacing-block 39 and the inner faces of the heads 40 and 41, whereby the said diaphragms respond to pressures in the chambers 43 and 45 for the movement of the plunger in one direction or the other, according to the variations of feed-water and steam pressures in the boiler system. The movement of the plunger 8 positively 105 sweeps the indicator over the graduated scale on the index-plate 5 and by direct reading indicates the difference of pressure between the boiler feed-water pressure and the steam pressure, without recourse to any 110 calculation on the part of the observer. The apparatus shown by Figure 8 is well adapted to be set up in the office of the chief engineer along with other gauges and instruments commonly found in such places. 115

I claim:

1. A direct-reading pressure-difference indicator having a graduated scale, an oil-chamber, an indicator moving in a body of oil in the said oil-chamber, whereby the operation of the indicator is stabilized and a prime-mover simultaneously subjected to the opposing pressures whose difference is to be indicated, the said prime-mover being connected with the indicator for the operation thereof. 120

2. A direct-reading pressure-difference indicator having an oil-chamber, a graduated scale carried thereby, an indicator passing through the said chamber and stabilized by a 130

body of oil therein, a reciprocatable prime-mover engaging with the indicator for operating the same, a diaphragm-head in which the prime-mover is located, and diaphragms by which the said head is suspended and which are operated by the pressures the difference of which is to be indicated, the said diaphragms acting upon the ends of the prime-mover for that purpose.

3. A direct-reading pressure-difference indicator having a reciprocatable operating-head, a graduated scale carried thereby and partaking of the movement thereof, a reciprocatable prime-mover mounted in the said head and formed midway of its length with a vertical passage, an indicator coacting at its upper end with the said scale and at its lower end passing downward through the said passage into the said head in which it is fulcrumed, and means for simultaneously subjecting the prime-mover to the opposed action of the pressures the difference of which is to be indicated by the indicator.

4. A direct-reading pressure-difference indicator having a graduated scale, an oscillatable indicator fulcrumed at its lower end, a reciprocating prime-mover through which the fulcrum end of the indicator passes for its operation thereby, and means for simultaneously subjecting the prime-mover to the opposed action of the pressures the difference of which is to be indicated by the indicator.

5. The combination with the reciprocatable operating-head of a follow-up pressure-regulator, of a direct-reading pressure-difference indicator mounted in the said head for bodily movement therewith and comprising a graduated scale, an indicator fulcrumed at its lower end in the said head, a reciprocatable prime-mover located co-axially within the said head and co-acting with the fulcrumed end of the indicator for oscillating the same; and means for simultaneously subjecting the ends of

the said prime-mover to the opposed action of the feed-water pressure and steam pressure of the follow-up pressure regulator.

6. The combination with the reciprocatable operating-head of a follow-up pressure-regulator, of diaphragms by means of which the said head is suspended, means for simultaneously subjecting the diaphragms to the feed-water and steam pressures of the regulator, and a direct-reading pressure indicator carried by the said head for bodily movement therewith and comprising a graduated scale, a reciprocatable prime-mover co-axially mounted within the said head for simultaneous subjection to the action of the respective diaphragms of the regulator; and an indicator oscillated by the said prime-mover and means interposed between the said diaphragms and the ends of the prime-mover for preventing the same from being embedded at its ends therein.

7. A direct-reading pressure-difference indicator having a reciprocatable operating-head, an oil-chamber carried thereby, a graduated scale, a reciprocatable prime-mover located co-axially within the said head in an axial passage therein connecting with the said oil-chamber, whereby the prime-mover is virtually floated in oil, an indicator fulcrumed in the said head, connected with the said prime-mover and passing through the oil in the said oil-chamber, and means for simultaneously subjecting the ends of the said prime-mover to the opposed action of the pressures the difference of which is to be indicated by the indicator.

In testimony whereof, I have signed this specification in the presence of two subscribing witnesses.
